(57) **CLAIM**

The ornamental design for a Firearm Accessory Connector as shown and described.

DESCRIPTION

FIG. 1 is a perspective front view of the Firearm Accessory Connector, which embodies my design;

FIG. 2 is a perspective rear view thereof;

FIG. 3 is a right side view thereof;

FIG. 4 is a left side view thereof;

FIG. 5 is a top view thereof;

FIG. 6 is a bottom view thereof;

FIG. 7 is a rear view thereof; and

FIG. 8 is a front view thereof.
